DOOR LOCK

Walter R. Schlage, Burlingame, Calif.

Application September 4, 1942, Serial No. 457,342

15 Claims. (Cl. 70—146)

This invention relates to door locks and especially to improvements and additions to the structure shown in my recent patent entitled "Door lock," issued November 17, 1942, Patent No. 2,302,380.

In the present application I have shown a spindle housing and a tubular spindle together with a latch bolt housing and a latch bolt mechanism which is substantially identical with the disclosure in my co-pending application. But in addition thereto, a new mechanism is disclosed which is contained in the tubular spindle. This mechanism forms the subject matter of the present application.

Broadly stated, the object of the present invention is to provide a key mechanism in one end of the tubular spindle which is longitudinally movable by manual operation; to provide mechanism actuated by such longitudinal movement for retracting the latch bolt; to provide a key mechanism which becomes rotatable by insertion of a key and by key rotation transmits rotary movement to the spindle to retract the latch bolt; and further, to provide a push button actuated dogging mechanism in the opposite end of the spindle whereby the key mechanism may be dogged against longitudinal movement but at the same time left free to be rotated by key operation.

The lock mechanism as a whole together with the mechanism forming the subject matter of the present application, is shown by way of illustration in the accompanying drawings, in which

Fig. 1 is a central vertical section of a door showing the lock inserted therein, said section being taken on line I—I of Fig. 2.

Fig. 2 is a horizontal section taken on line II—II, Fig. 1.

Fig. 3 is a vertical section taken on line III—III, Fig. 2.

Fig. 4 is a section similar to Fig. 2 showing the key mechanism dogged against longitudinal movement.

Fig. 5 is a section similar to Fig. 2 showing the key mechanism moved longitudinally and the latch bolt retracted.

Fig. 6 is a perspective view of the lock mechanism as a whole, the only parts missing from this view being the inner escutcheon plate and the inner door knob.

Fig. 7 is a perspective view of the cylinder lock plug.

Fig. 8 is a perspective view of a cap applied to the outer end of a housing member in which the cylinder plug shown in Fig. 7 is mounted.

Fig. 9 is a perspective view of the housing containing the cylinder plug and to which the cap in Fig. 8 is applied.

Fig. 10 is a perspective view of the spindle housing.

Fig. 11 is a perspective view of the inner push button and a dogging bar actuated thereby.

Fig. 12 is a perspective view looking at one side of the spindle.

Fig. 13 is a perspective view of a dog which is connected with the dogging bar shown in Fig. 11.

Fig. 14 is a perspective view of the retractor lever; and

Fig. 15 is a perspective view of the spindle shown in Fig. 12, but showing the opposite side thereof.

Referring to the drawings in detail and particularly Figs. 1 and 2, A indicates a door in which is drilled or bored two holes, one indicated at 2 and the other at 3. These holes are disposed at right angles at each other and intersect. Insertable into the hole 3 is a latch bolt housing, generally indicated at B, see Figs. 1, 2 and 6. On the outer end of this housing is a face plate

25 4 having screw holes formed at each end to permit the housing to be secured within the hole to the edge of the door by ordinary screws. Slidably mounted in the housing B is a retractor plate 5 on the outer end of which is secured a latch bolt 6, and formed adjacent the inner end of the retractor plate is an elongated slot 7, see Fig. 3, which terminates in a right angular shoulder 8. This slot is essential as it permits insertion of a spindle housing and a spindle, as will now be described, and it also permits longitudinal movement of the retractor plate when the latch bolt is to be retracted.

Extending crosswise of the door through the opening 2, and also through openings formed 30 in the sidewalls of the latch bolt housing, see Figs. 6 and 10, is a tubular spindle housing, generally indicated at C, and extending through said housing is a tubular spindle, generally indicated at D, see Figs. 12 and 15, which is cross-slotted midway of its length to form a roll back member 9. The tubular spindle housing C is also cross-slotted, as indicated at 9a. The roll back member 9 aligns with this slot when the spindle is properly positioned within the spindle housing, and shoulder 8 of the retractor plate extends through the slot 9a and engages the roll back member 9, see Fig. 3, so that rotation of the spindle will cause the roll back member to engage the shoulder 8 and thereby force it rearwardly to retract the latch bolt 6. A spring 10

35

40

45

50

55

is interposed between the rear end of the retractor plate and the inner end of the latch bolt housing, and this spring serves a function of normally maintaining the latch bolt in projected position.

By referring to Figs. 1 and 10 it will be noted that the opposite ends of the spindle housing are threaded and that these threaded ends project beyond the inner and outer faces of the door A. These projecting ends are provided with screw threads to receive on the outer face of the door a head member, generally indicated at E and on the inner side of the door an escutcheon plate F. The head member E is provided with a handle G thereby permitting the lock as a whole to function as a front door lock, but this handle is not essential as the head member E could be shaped in the form of a knob, see the dotted lines 11, so that a pull can be exerted to open the door as will hereinafter be described. The knob indicated in dotted lines will, however, only function in the manner of a drawer knob or pull as it cannot be rotated. The ordinary door knob H secured on the inner end of the spindle is however rotatable to rotate the spindle and thereby to retract the latch bolt.

The mechanism so far described is substantially identical to that disclosed in my former patent heretofore referred to, and for that reason has been only briefly described. The present invention relates almost entirely to mechanism which is placed within the tubular spindle D. This mechanism, briefly stated, comprises a key actuated mechanism, generally indicated at J, see Fig. 2, disposed in the outer end of the tubular spindle, which may be longitudinally moved within the spindle by manual operation to cause retraction of the latch bolt 6, thus making it possible to retract the latch bolt by merely applying thumb pressure to the end of the key mechanism, or in other words, to permit it to function as a push button, which, when depressed by thumb action, will permit opening of the door. This key mechanism is also rotatable by insertion of the key, and when key rotated transmits rotary motion to the spindle and thereby causes retraction of the latch bolt.

Other means are provided within the spindle for dogging the key mechanism against longitudinal movement. This dogging mechanism is actuated by a push button mounted in the inner end of the tubular spindle, thus it is possible to dog the key mechanism against operation except by insertion of the key as the key mechanism may be rotated even though it is dogged against longitudinal movement.

The key mechanism specifically described comprises a tubular housing generally indicated at 14, see Figs. 2 and 9. The inner end of this housing has a lug 15 formed thereon on which is mounted a pin 16. This pin extends into a slot 17 formed in one end of the tubular spindle housing, see Fig. 10, and thereby secures the housing 14 against rotation, but at the same time permitting longitudinal movement thereof. Mounted within the housing 14 is a cylinder key plug 18, see Fig. 7, which carries a series of tumblers 18a and which also has a key way formed therein. This key way is open at the outer end to permit insertion of a key 19, see Figs. 1 and 2, and the inner end is provided with a lug 20, the function of which will hereinafter be described, also a pin is secured in the plug at the point indicated at 21, and this pin extends into an opening 22, see Fig. 12, so as to permit

the plug when rotated to transmit rotation to the spindle, that is, shoulders 22a are formed on opposite sides of the opening 22 and when the plug is rotated by means of the key, the pin 21 will engage one or another of these shoulders and thereby rotate the spindle.

Referring again to Fig. 9 which shows the housing 14, it will be noted that an elongated slot 14a is formed therein. This slot aligns with the tumblers 18a and permits the tumblers to enter, thus when the key is inserted into the plug 18, the tumblers will be retracted and the plug may be rotated with relation to the housing 14, but when the key is removed the tumblers will project into said slot 14a and the plug will then be secured against rotation. A cap 23 is applied to the outer end of the tubular housing 14 and this cap together with the outer end of the plug 18 forms a push button which functions as will hereinafter be described.

By referring to Figs. 2 and 14, it will be noted that a retractor lever 25 is disposed within the spindle just ahead of the lug 20 formed on the inner end of the cylinder plug. This lever is pivoted on a pin 26 extending through and secured in the walls of the spindle. See the dotted lines 26 in Fig. 15. Also the spindle is slotted at this point to permit introduction of the lever. The inner end of the lever has a shoulder 27 formed thereon, and this shoulder engages the shoulder 8 of the retractor plate.

The function of the key mechanism and the lever is as follows:

If it is desired to open the door from the exterior it is only necessary to grasp the handle G and apply thumb pressure to the cap 23 and the outer end of the cylinder plug 18. This pressure causes the entire key mechanism to move inwardly and as it moves inwardly the lug 20 engages the rear end of the retractor lever 25 and thereby swinging it about its pivot 26 and causing the forward end or shoulder 27 to engage the shoulder 8 of the retractor plate to force it inwardly and thereby retract the latch bolt 6 when the door may be opened by pulling on the handle G, or the knob indicated in dotted lines at 11. Upon releasing thumb pressure on the outer end of the key mechanism, spring 10 will return all parts to normal position.

A dogging member generally indicated at 30 and mounted adjacent the free end of the lever 25 may be pushed inwardly to assume the position shown in Fig. 4 by means of a push button indicated at 31, and when the dog assumes the position shown in Fig. 4, it will obviously be impossible to impart longitudinal movement to the key mechanism and the key mechanism is thus dogged against depression or push button action to open the door. It may, nevertheless, be opened providing a person has the proper key, as by inserting a key the tumblers will be withdrawn from the slot 14a of the housing 14, thus leaving the cylinder plug 18 free to be rotated by the key, and when it is so rotated, pin 21 carried by the inner end of the cylinder plug will engage one or another of the shoulders 22a and the spindle thereby rotating it, such rotation causing the roll back member 9 of the spindle to engage the shoulder 8 of the retractor plate, see Fig. 3, and thereby cause it to move inwardly and to retract the latch bolt, thus it is possible to open the door from the exterior by push button operation only when the dog is undogged and it is possible to open the door by key action when the dog is in dogging position.

The dogging mechanism consists of a rod like member 30, see Fig. 13, which is slotted as at 32 to permit it to be attached to a dogging bar 33 by means of a pin, see Figs. 2, 11 and 13. The dogging bar carries the push button 31 at its outer end and this push button projects through the inner end of the spindle and the knob H carried thereby. The pin which connects the dogging member 30 and the bar 33 projects beyond the outer face of the dog 30 and into a cross-slot 35 formed in the spindle, see Fig. 12. A second slot or depression 36 is formed midway of the length of the slot 35 and the pin 37 normally rests in the depression 36 when the dog is undogged, but when the push button 31 is pressed inwardly the pin 37 is moved out of the slot 36 into the slot 35 and may then be rotated to either side and the push button 31 is thus secured against return movement until it is again rotated to cause the pin 37 to register with the depression 36. When pin 37 engages the slot 35 at either side of the depression 36 the forward end of the dog which is flared, engages the forward end of the retracting lever and thus retains it in dogging position. A spring 40 is interposed between the button 31 and a shoulder 41 within the spindle and this returns the push button 31 and dog 30 to retracted position whenever the button is rotated to bring the pin 37 in alignment with depression 36, thus the normal position of the push button 31 is its extended position, as it must be manually pushed inwardly and then rotated to one side or another before the dog can assume dogging position. When the door is dogged from the inner side it is locked against being opened from the outside except by an authorized person having the proper key, as in dogging position the push button action of the key mechanism cannot be utilized. On the other hand it can be rotated to open the door when the proper key is inserted.

Having thus described my invention, what I desire to secure by Letters Patent is

1. In a lock, a latch bolt, a tubular rotatable spindle, means actuated by rotation of the spindle for retracting the latch bolt, a push button mounted in one end of the spindle, means actuated by said push button for retracting the latch bolt, a push button mounted in the other end of the spindle, and means actuated by said last-named push button for rendering the first-named push button inoperative to retract the latch bolt.

2. In a lock, a latch bolt, a tubular rotatable spindle, means actuated by rotation of the spindle for retracting the latch bolt, a push button mounted in one end of the spindle, means actuated by said push button for retracting the latch bolt, a push button mounted in the opposite end of the spindle, and means actuated by said last-named push button for dogging the first-named push button against operation.

3. In a lock, a latch bolt, a single tubular spindle, a depressable push button mounted at the outer end of the spindle and longitudinally movable therein, means carried by and within the spindle actuated by depression of the push button to retract the latch bolt, and a roll-back member on the spindle actuated by rotation of the spindle for retracting the latch bolt.

4. In a door lock, a latch bolt, a spindle, key actuated means in the spindle for rotating the spindle, means actuated by key rotation of the spindle for retracting the latch bolt, said key actuated means being longitudinally movable in the spindle by manual operation, a lever piv-

otally mounted in the spindle and being engaged and swung about its pivot during longitudinal movement of the key mechanism, and means actuated by pivotal movement of the lever to retract the latch bolt.

5. In a door lock, a latch bolt, a spindle, a rollback member on the spindle, key actuated means in the spindle for rotating the spindle to cause the rollback to retract the latch bolt, said key actuated means being longitudinally movable in the spindle by manual operation, means actuated by longitudinal movement of the key mechanism for retracting the latch bolt, and a knob for rotating the spindle to cause the rollback to retract the latch bolt.

15 6. In a lock, a latch bolt, a rotatable tubular spindle having a rollback member whereby the latch bolt is retracted, a depressable push button mounted in the outer end of the spindle means actuated by the push button to retract the latch bolt, manipulative means within the inner end of the spindle to render the push button non-depressable, and key operated means within the push button adapted to rotate the spindle to retract the latch bolt when the push button is rendered non-depressable.

20 7. In a lock, a latch bolt, a tubular spindle, a push button extending through one end of the spindle, a key mechanism within the push button, means carried by the spindle whereby depression of the push button or rotation of the spindle or rotation of the key mechanism will retract the latch bolt, and other means within the spindle whereby the push button is rendered non-depressable, leaving the spindle and key mechanism free to retract the latch bolt.

25 8. In a lock, a latch bolt, a hollow spindle, a push button extending through one end of the spindle and a knob mounted on the other end, means whereby depression of the push button will retract the latch bolt, means whereby rotation of the spindle by the knob will retract the latch bolt and manually operative means extending through the knob, adapted to either permit or prevent operation of the push button, said manual means leaving the knob free to rotate the spindle and retract the latch bolt at all times.

30 9. In a lock, a latch bolt, a hollow spindle, a push button extending through one end of the spindle, a knob mounted on the other end, means whereby depression of the push button will retract the latch bolt, means whereby rotation of the spindle by the knob will retract the latch bolt, manually operative means extending through the knob, adapted to either permit or prevent operation of the push button, said manual means leaving the knob free to rotate the spindle and retract the latch bolt at all times, and key actuated means within the push button whereby the latch bolt can be retracted when the push button is rendered inoperative.

35 10. In a lock, a latch bolt, a tubular spindle, a latch bolt retractor member pivotally mounted within the spindle, a depressable push button projecting from the outer end of the spindle adapted to impart swinging movement to the retractor member to retract the latch bolt, and dogging means projecting from the inner end of the spindle adapted to dog the retractor member against swinging movement.

40 11. In a lock, a latch bolt, a rotatable tubular spindle having a rollback member to retract the latch bolt, a pivoted latch bolt retractor mounted within the spindle, a sliding element in one end of the spindle adapted to operate the pivoted

latch bolt retractor, and another sliding element within the other end of the spindle, adapted to render the pivoted retractor inoperative.

12. In a lock, a latch bolt, a rotatable tubular spindle having a rollback member to retract the latch bolt, a longitudinally movable and rotatable key mechanism extending into the outer end of the spindle and movable independently of the spindle, a knob on the inner end of the spindle, means whereby longitudinal movement of the key mechanism or rotation of the spindle by either key or knob will retract the latch bolt, and dogging means within the knob, adapted to prevent longitudinal movement of the key mechanism, but leaving the key and knob free to rotate the spindle at all times.

13. In a front door lock, latch bolt housing containing a latch bolt, a spindle housing disposed at right angles thereto and containing a rotatable spindle, a rollback member spindle to retract the latch bolt, a head member secured to one end of the spindle housing, a push button longitudinally movable in said head member, a rotatable key mechanism in the push button, means actuated by rotation of the key mechanism for rotating the spindle to retract the latch bolt, and means actuated by longitudinal movement of the push button for retracting the latch bolt independently of the rollback member.

14. In a front door lock, latch bolt housing containing a latch bolt, a spindle housing disposed at right angles thereto and containing a rotatable spindle, a rollback member spindle to retract the latch bolt, a head member secured to one end of the spindle housing, a push button longitudinally movable in said head member, a rotatable key mechanism in the push button, means actuated by rotation of the key mechanism for rotating the spindle to retract the latch bolt, means actuated by longitudinal movement of the push button for retracting the latch bolt independently of the rollback member, and means operable from the inner side of the lock for dogging the push button against longitudinal movement, said means leaving the push button free to be rotated by the key mechanism.

15. In a lock, a latch bolt, a rotatable tubular spindle, having a roll-back member whereby the latch bolt is retracted, a rotatable key actuated mechanism longitudinally movable in one end of the spindle, and means whereby either longitudinal movement of the key actuated mechanism or rotation by a key will retract the latch bolt.

WALTER R. SCHLAGE.
